HOLLOW CEMENT BLOCK

David Stanley Corwin, Greenport, N. Y.

Application June 4, 1934, Serial No. 728,930

5 Claims. (Cl. 72—42)

This invention relates to new and useful improvements in a hollow cement block.

The invention has for an object the construction of a block as mentioned which is characterized by the provision of an open mesh reinforcement material having a bottom and side walls, and supporting a moisture-proof plate extending across the top edges of the side walls and held together in a unit by cement covering the inner and outer sides of said open mesh reinforcement material and plate. A feature of the construction is that the block will be light in weight, and since it is hollow it will float; it will also be water-proof because of its cement construction and moisture-proof because of the moisture-proof plate on one face, said face preferably should be used as the front face.

Still further the invention proposes the construction of a block as mentioned in the previous paragraph which is arranged in such a manner that the front face may be finished ornamentally into different effects as desired.

Still further it is proposed to produce a block as mentioned which requires no backing or furring and which may be manufactured without resorting to pressures.

Still further the invention proposes to so arrange the block that it may be built with or, without a form though of course, a form will expedite its manufacture.

Still further the invention proposes the teaching of a method by which the block may be manufactured.

Another one of the objects of this invention is the construction of a block which is characterized by a pair of moisture-proof plates slightly spaced from each other and in one of the walls thereof and in other respects resembling the block previously described as to characteristics.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a hollow cement block constructed according to this invention.

Fig. 2 is a transverse sectional view taken on the line 2—2 of Fig. 1.

Fig. 3 is a perspective view of the open mesh material, illustrated in Fig. 2 used in the manufacture of the block.

Fig. 4 is a perspective view of a form in which the block may be conveniently manufactured.

Fig. 5 is a sectional view similar to Fig. 2 illustrating a modification of the invention.

Fig. 6 is a similar view to Fig. 2 but showing another modification of the invention.

The hollow concrete block according to this invention includes open mesh reinforcement material 10 having a bottom 10' and side walls 10^a and associated with a moisture-proof plate 11, such as glass, extending across the top edges of the side walls and held in an integral unit by cement 12 arranged upon the sides of the open mesh material and the plate.

More particularly the open mesh material 10 is conventional reinforcement material used in concrete reinforcement constructions formed from sheets stamped or in any other manner formed with openings.

More particularly, the open mesh reinforcement 20 10 has the side walls 10^a formed with in-turned bent edges 10^b upon which the moisture-proof plate 11 is supported during the manufacture of the block. Since the open mesh material is of open construction some of the cement 12 25 will enter from the inside and extend to the outside as illustrated in Fig. 2 of the drawing, so that in reality the reinforcement material 10^a will be imbedded in the hollow concrete cement 30 form. The side of the block provided with the moisture-proof plate 11 constitutes the front of 35 the block and may be finished in any suitable fashion. For example a tile 13 is cemented together with it. While this particular design is shown it should be borne in mind that the cement 40 12 itself may be finished in a satisfactory manner or any other type of finish known at the present time or to be discovered in the future may be applied to the block.

In Fig. 6 the tile has been substituted by an 45 ornamental layer of concrete cement 13' on which any suitable design may be formed.

The process for manufacturing the block consists in the provision of a form such as illustrated in Fig. 4 including a body consisting of a bottom wall 14 and the side walls 15. This body is open 50 at the top. The open mesh reinforcement material 10 illustrated in Fig. 3 may be set into the body and the parts are of such size that there will be a slight area between the outer faces of 55

the reinforcement material 10 and the inner faces of the body.

The first step in the manufacture of the block consists in placing cement material within the body upon the bottom 14. Next the open mesh reinforcement material is placed within the body and cement is filled in between the mesh reinforcement and forced into the reinforcement and the body by a suitable tool so that some of the cement will cover the inner side of the reinforcement. In any event it is proposed to cause the cement to encircle the bottom and the sides, also the inner sides of the open mesh material. The next step in the process consists in merely 15 pressing the moisture-proof plate 11 in position upon the inturned ends 10^c. Then cement is added at the top and in this manner the hollow block is concluded.

In Fig. 5 another embodiment of the invention is illustrated in which an arrangement is provided wherein the block is formed with a pair of moisture-proof plates 11 and 11^a slightly spaced from each other. More particularly the block includes open mesh material 10^c having a bottom 25 wall 10^d and side walls 10^e. The upper free edges 10^f of the side walls are turned inwards. A flange 10^g is extended inwards from the side walls of the open mesh material 10^c and is spaced slightly downwards from the inturned top edges 10^f. This flange 10^g extends inwards to a greater distance than the inturned edges 10^f. The arrangement is such that the moisture-proof plate 11^a may be supported upon the flanges 10^g. The compass of the plate 11^a is of a smaller size than 30 the area between the inturned edges 10^f so that the plate may easily assume its position. The top moisture-proof plate 11 is of a size so as to be capable of resting upon the inturned edges 10^f.

The block is manufactured with the cement 40 engaged upon the outer walls of the reinforcement material and over the top of the top moisture-proof plate 11^a. The arrangement is such that there is a small area 16 between the plates 11 and 11^a which serves to prevent or retard 45 conduction through the front wall of the block.

The process of manufacturing the block illustrated in Fig. 2 consists in arranging the open mesh reinforcement material 10^c within the form, such as illustrated in Fig. 4, in a manner so that 50 there is cement upon the inner and outer faces of the sides and bottom thereof. Then the plate 11^a is placed in position, and finally cement is engaged over the top of the plate 11 and caused to join with the cement at the sides. The front face of the block may be finished with a tile, such as tile 13.

In actual use these waterproof cement blocks may be also filled with cement or other suitable material through holes by boring communicating holes between the adjacent blocks after they 55 are stacked to form a wall, partition, etc.

While I have shown and described the preferred embodiment of my invention, it is to be understood that I do not limit myself to the precise

construction herein disclosed and the right is reserved to all changes and modifications coming within the scope of the invention as defined in the appended claims.

Having thus described my invention, what I claim as new, and desire to secure by United States Letters Patent is:—

1. A hollow cement block, comprising open mesh reinforcement consisting of mesh material having a bottom and side walls in the form of a box with an open top, a glass plate extending across the top edges of said side walls, and cement covering the inner and outer sides of said open mesh material and said plate and binding these parts together into a hollow unit. 10

2. A hollow cement block, comprising open mesh reinforcement consisting of mesh material having a bottom and side walls in the form of a box with an open top, a glass plate extending across the top edges of said side walls, and cement covering the inner and outer sides of said open mesh material and said plate and binding these parts together into a hollow unit, the top edges of the reinforcement material being bent inwards and supporting said moisture- 20 proof plate. 25

3. A hollow cement block, comprising open mesh reinforcement consisting of mesh material having a bottom and side walls in the form of a box with an open top, a glass plate extending 30 across the top edges of said side walls, and cement covering the inner and outer sides of said open mesh material and said plate and binding these parts together into a hollow unit, the side of the block provided with the moisture- 35 proof plate constituting the front of the block, and being finished as the front of the block.

4. A hollow cement block, comprising open mesh reinforcement material having a bottom and side walls, a flange extended inwards from the side walls and spaced slightly down from the top edge, a moisture-proof plate resting upon said flange, a second moisture-proof plate resting across the tops of said side walls, and cement covering the inner and outer sides of said open mesh reinforcement material and top plate and engaging the edges of said second plate and holding the parts in a hollow unit. 40

5. A hollow cement block, comprising open mesh reinforcement material having a bottom and side walls, a flange extended inwards from the side walls and spaced slightly down from the top edge, a moisture-proof plate resting upon said flange, a second moisture-proof plate resting across the tops of said side walls, and cement covering the inner and outer sides of said open mesh reinforcement material and top plate and engaging the edges of said second plate and holding the parts in a hollow unit, the top edges of said side walls being bent inwards and said top plate resting thereon. 50 55 60

DAVID STANLEY CORWIN.
